EAR TAG FOR ANIMALS

Donald David Fearing, 924 Arbor,
Mahtomedi, Minn. 55115

Filed Nov. 10, 1969, Ser. No. 20,002

Term of patent 14 years

Int. Cl. D30—99

U.S. Cl. D30—43

FIG. 1

FIG. 2

FIG. 3

FIG. 4

FIG. 1 is a side elevational view of an ear tag for animals, showing my new design;

FIG. 2 is a top plan view;

FIG. 3 is an end elevational view showing the right hand end as viewed in FIG. 1; and

FIG. 4 is an end elevational view showing the left hand end as viewed in FIG. 1.

I claim:

The ornamental design for an ear tag for animals, as shown.
